[57] CLAIM

The ornamental design for an electric shaver, substantially as shown and described.

DESCRIPTION

FIG. 1 is a front elevational view of an electric shaver showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a longitudinal section taken on the center line A-A' of FIG. 1; and

FIG. 8 is a transverse section taken on the line B-B' of FIG. 2.
